H. A. DOUGLAS.
CIRCUIT CONTINUING DEVICE,
APPLICATION FILED JULY 23, 1917.

1,299,147.

Patented Apr. 1, 1919.

UNITED STATES PATENT OFFICE.

HARRY A. DOUGLAS, OF BRONSON, MICHIGAN, ASSIGNOR TO DOUGLAS & RUDD MFG. CO.
OF BRONSON, MICHIGAN, A CORPORATION OF MICHIGAN.

CIRCUIT-CONTINUING DEVICE.

1,299,147.

Specification of Letters Patent.

Patented Apr. 1, 1919.

Application filed July 23, 1917. Serial No. 182,198.

To all whom it may concern:

Be it known that I, HARRY A. DOUGLAS, a citizen of the United States, residing at Bronson, in the county of Branch and State 5 of Michigan, have invented a certain new and useful Improvement in Circuit-Continuing Devices, of which the following is a full, clear, concise, and exact description.

My invention relates to circuit continuing 10 devices and has for its general objects the provision of an improved formation thereof whereby their component parts may readily and quickly be assembled by simple and efficient means and may readily be disassembled.

15 The invention finds a most useful embodiment in the formation of connecting plugs.

The device of my invention is inclusive of a contact carrier or core and a jacket therefor with which such core is preferably separably assembled by means of interengaging 20 coupling formations provided upon the jacket and core. The jacket is preferably inclusive of a body portion and a cap, the body portion having coupling engagement 25 with the core while the cap functions to maintain the assembly of the jacket body portion and the core. Current conducting means desirably extends into the core laterally thereof, but to which arrangement the 30 invention is not to be limited, and when so extended it desirably serves as an aid in relatively positioning the cap and body portions of the jacket in the process of their assembly.

By means of the interengaging coupling 35 formations upon the jacket body and the core relative longitudinal movement of these parts is prevented; relative rotary movement of the cap and core is prevented by the interengaging formations provided thereon; and 40 relative rotary movement of the cap and body portions of the jacket is prevented by interengaging formations provided upon these parts.

My invention in all of its aspects will be 45 fully explained by reference to the accompanying drawing showing the preferred embodiment thereof and in which Figure 1 illustrates the circuit extending plug of my invention in longitudinal section, there being 50 also illustrated a circuit coupler into the shell of which the plug is inserted; Fig. 2 is a view on line 2-2 of Fig. 1; Fig. 3 is a view on line 3-3 of Fig. 1; Fig. 4 illustrates component parts of the circuit extending 55 plug of my invention in separated relation;

Fig. 5 is a view taken on line 5-5 of Fig. 4; and Fig. 6 is a view taken on line 6-6 of Fig. 1.

Like parts are indicated by similar characters of reference throughout the different 60 figures.

The circuit extending plug of my invention may be employed in conjunction with any suitable device whereby the plug is instrumental in connecting a translating device with a circuit that is to supply the translating device with current. Such a device is shown in Fig. 1 and partially in Fig. 3, the device shown being inclusive of a cylindrical metallic current conducting shell 1 70 which has bayonet slots 2 at one end for receiving the metallic bayonet pins 3 that project from the metallic sheath 4 provided about the base of the lamp 5 and adapted for electrical contact with the shell 1. This 75 sheath constitutes one terminal of the lamp as the structure illustrated is a single pole connector. This lamp base also carries a centrally disposed contact 6 which is insulated from the sheath 4 and which contact 6 80 constitutes the remaining terminal of the lamp 5. The shell 1 incloses a contact carrier 7 of insulating material. A spring 8 presses the contacts 9 and 10, that are carried by the carrier 7, outwardly, this spring forcing the engagement of the contact 9 with the contact 6. The shell 1 is grounded or otherwise connected with one terminal of a source 85 of current. The contacts 9 and 10 are connected with the other terminal of the source 90 of current by a circuit extending plug of my invention.

The circuit extending plug of the invention is inclusive of a metallic jacket that has a cylindrical metallic body portion 11 and a 95 circular metallic cap portion 12 having a cylindrical skirt 12¹. The body portion 11 of this jacket and the metallic shell 1 are provided with interengaging coupling formations that are preferably in the nature of 100 bayonet pins or lugs 13 upon the jacket body 11 and complementary bayonet slots 14 in the shell 1. The jacket body 11 is assembled with a contact carrying cylindrical core 15, this assembly being desirably effected by interengaging coupling formations provided 105 upon the core and jacket body and which are preferably a bayonet pin 16 carried by the core and a bayonet channel 17 in the jacket body. The contact carrier 15 and the jacket 110

body 11 are prevented from having movement longitudinally with respect to each other when the bayonet pin 16 and bayonet channel 17 are in engagement although they 5 are adapted to have relative rotary movement which is prevented as will be later described. The jacket body 11 and contact carrier 15 are prevented from having rotary movement with respect to each other by 10 means of the jacket cap 12 which is coupled with the contact carrier or core 15 in a manner to be held from rotation with respect thereto and which jacket cap is so engaged with the jacket body 11 as to be held from 15 rotation with respect thereto. The jacket cap 12 is desirably assembled with the contact carrier 15 by means of a screw 18 whose stem is in threaded engagement with the carrier 15 and whose head presses the jacket 20 cap into firm engagement with the contact carrier or core 15.

To supplement the function of the screw 18 in preventing rotation of the cap 12 with respect to the contact carrier 15, I provide 25 a lug or pin 19 that extends inwardly from the cap 12 and enters the recess 20 upon the adjacent end face of the carrier 15. The interengagement between the jacket body 11 and the jacket cap 12 (whereby rotation of these two elements with respect to each other is prevented) is preferably effected by the construction most clearly illustrated in Fig. 2 where the cap 12 is shown as being provided with a rib 21 30 formed in the skirt of the cap and extending longitudinally thereof and the adjacent end of the jacket body 11 is shown as being formed with a longitudinal groove 22 that receives the rib 21. 35 The contact carrying core 15 preferably has a cylindrical enlargement 15¹ at the outer end thereof and which core enlargement is encircled by the cylindrical enlargement 11¹ of the jacket body 11. The 40 core enlargement 15¹ engages the shoulder formed where the jacket enlargement 11¹ merges with the smaller part of the jacket body 11. The jacket enlargement 11¹ is preferably of a size sufficient to afford an 45 annular space between it and the core enlargement 15¹ and into which space the flanged end of the short sleeve 23 projects. This sleeve constitutes a part of a conductor covering and the flange thereof constitutes 50 an enlargement of such covering. This sleeve closely engages the serving or other covering 24 for the conductor 25. This conductor terminates in a plug having a tip 26 that is provided with a groove 27 55 that is adapted to receive the tip of the stem of the plunger contact 28. This plug, in the embodiment of the invention illustrated, is received in a passage that extends laterally of the core into communication 60 with the longitudinal passage in such core

that receives the cylindrical contact 29 and the plunger contact 28. The plunger contact 28 is assembled with the contact 29, the plunger contact being pressed outwardly by a coiled spring 30 contained in 70 the hollow portion of the contact 29. As the construction illustrated is a single pole construction (but to which single pole construction the invention is not to be limited) there is but one contact 29 and this contact 75 is co-axial with the core 15 that carries it so as to be in position to be engaged by the spring pressed contact 10.

In the assembly of the parts of the circuit extending plug of my invention the 80 plug portion having the tip 26 is first inserted into the core enlargement 15¹ to have engagement with the spring pressed contact 28 whereafter the core 15 is assembled with the jacket body 11 by effecting engagement between the bayonet pin 16 and the bayonet channel 17. The jacket enlargement 11¹ is desirably provided with a peripherally elongated open slot 31 that 85 permits the movement of the sleeve 23 and 90 the conductor surrounded thereby longitudinally of the jacket body when this jacket body and the core are in the process of assembly. When the bayonet pin 16 and the bayonet channel 17 are in full engagement, the flange upon the inner end of the sleeve 23 is disposed in the annular space that intervenes between the jacket enlargement 11¹ and the core enlargement 15¹. The 95 skirt 12¹ of the cap 12 has an open slot 100 32 of a peripheral length co-extensive with the diameter of the sleeve 23. After the bayonet pin 16 has been placed home in the bayonet channel 17 the sleeve 23 engages one end of the slot 31 (Fig. 3) whereafter the cap 12 is slipped over the jacket enlargement 11¹ while the slot 32 is in register with the sleeve 23. This sleeve 23 thus 105 serves to position the cap with its rib 21 in register with the groove 22 and its pin 110 19 in register with the recess 20, such sleeve 23 thereby facilitating the assembly of the jacket cap 12 with the jacket body 11. After the cap has been fully slipped into position the screw 18 is applied to maintain all of 115 the parts in assembly. By merely withdrawing the screw the parts of the circuit extending plug may readily be disassembled.

While I have herein shown and particularly described the preferred embodiment of my invention I do not wish to be limited to the precise details of construction shown as changes may readily be made without departing from the spirit of my invention, 125 but having thus described my invention I claim as new and desire to secure by Letters Patent the following—

1. A circuit continuing device including a contact carrier; a jacket for the carrier com- 130

- prising cap and body portions, said body and carrier having interengaging bayonet pin and channel formations permitting said body and carrier to be slid into engagement 5 by their relative longitudinal movement and preventing their relative longitudinal movement when they are relatively turned after being slid into engagement, the cap and body having interengaging formations permitting 10 their relative longitudinal movement and preventing their relative turning movement; and means for fastening the cap and carrier together to prevent their relative turning movement to prevent the body and carrier from turning relatively and to prevent relative longitudinal movement of the carrier and cap to hold the cap and body in assembly.
2. A circuit continuing device including a contact carrier; a jacket for the carrier comprising body and cap portions, said body and carrier having interengaging formations permitting their relative turning movement and preventing their relative longitudinal movement, the cap and body having interengaging formations permitting their relative longitudinal movement and preventing their relative turning movement; and means for fastening the cap and carrier together to prevent their relative turning movement to prevent the body and carrier from turning relatively and to prevent relative longitudinal movement of the carrier and cap to hold the cap and body in assembly.
3. A circuit continuing device including a contact carrier; a jacket for the carrier comprising cap and body portions, said body and carrier having interengaging bayonet pin and channel formations permitting said body and carrier to be slid into engagement by their relative longitudinal movement and preventing their relative longitudinal movement when they are relatively turned after being slid into engagement, the cap and body having interengaging formations permitting their relative longitudinal movement and preventing their relative turning movement; and means for preventing relative turning movement between the cap and carrier to prevent the body and carrier from turning relatively.
4. A circuit continuing device including a contact carrier; a jacket for the carrier comprising body and cap portions, said body and carrier having interengaging formations permitting their relative longitudinal movement and preventing their relative turning movement; and means for preventing relative turning movement between the cap and carrier to prevent the body and carrier from turning relatively.
5. A circuit continuing device including a contact carrier; a jacket for the carrier comprising body and cap portions, said body and carrier having interengaging formations which, in one adjustment, permit their relative longitudinal movement and, in another adjustment, permit their relative turning movement, these interengaging formations preventing relative longitudinal movement of said body and carrier when they are relatively turned, the cap and body having interengaging formations permitting their relative longitudinal movement and preventing their relative turning movement; and means for fastening the cap and carrier together to prevent their relative turning movement to prevent the body and carrier from turning relatively and to prevent relative longitudinal movement of the carrier and cap to hold the cap and body in assembly.
6. A circuit continuing device including a contact carrier; a jacket for the carrier comprising body and cap portions, said body and carrier having interengaging formations which, in one adjustment, permit their relative longitudinal movement and, in another adjustment, permit their relative turning movement, these interengaging formations preventing relative longitudinal movement of said body and carrier when they are relatively turned, the cap and body having interengaging formations permitting their relative longitudinal movement and preventing their relative turning movement; and means for preventing relative turning movement between the cap and carrier to prevent the body and carrier from turning relatively.

In witness whereof, I hereunto subscribe my name this 19th day of July A. D., 1917.

HARRY A. DOUGLAS.
